Specification of Letters Patent.

Patented Jan. 8, 1918.

Application filed April 12, 1917. Serial No. 161,608.

To all whom it may concern:

Be it known that I, HENRY P. CLAUSEN, a citizen of the United States, residing at Mount Vernon, in the county of Westchester and State of New York, have invented certain new and useful Improvements in Telephone Systems, of which the following is a full, clear, concise, and exact description.

This invention relates to telephone systems, and more particularly to such systems in which a plurality of subscribers' stations are connected to the same line circuit.

In telephone systems of this type heretofore used there is no means by which an operator at a central office may readily determine which of the plurality of stations connected with the line has initiated a call. The present invention provides a simple system in which a very small amount of apparatus is required for enabling the operator to determine which of a plurality of stations on the line has initiated a call.

In accordance with the feature of this invention, a telephone line circuit, to which there are connected a plurality of subscribers' stations is equipped with a single electromagnet controlling a plurality of tuned vibrating reeds, which are selectively responsive to the vibration of similarly tuned reeds located at the various stations and set in motion when a call is initiated. At the central office, there are line signals controlled by the tuned reeds thereat.

This invention is illustrated in the accompanying drawing, wherein conductors 5 and 6 constitute a line circuit to which is connected a plurality of subscribers' stations A, B, C and D. This line circuit terminates at a central office in a plurality of jacks 10, 11, 12 and 13. Connected with the line conductor 6 is the winding of an electromagnet 7, which acts upon four tuned reeds 20, 21, 22 and 23. Each of these reeds is of a different length and is, therefore, tuned to respond to a different frequency of vibration. At the stations there are located reeds 30, 31, 32 and 33, one being at each station. Each of these reeds is of a different length and therefore has a different rate of vibration. The reed at each station is adapted to be set in vibration when the receiver thereat is removed from the switchhook to initiate a call. The vibrating reeds at the subscribers' stations may, therefore, be considered as generators of currents of different frequencies. Each

of the reeds controlled by electromagnet 7, when responding to the proper frequency, closes an energizing circuit for a relay controlled thereby, for example, reed 20 controls relay 40; reed 21 controls relay 41; 60 reed 22 controls relay 42; and reed 23 controls relay 43. These relays respectively control line signaling lamps 50, 51, 52 and 53 associated respectively with the jacks 10, 11, 12 and 13.

Referring now to the operation of the system disclosed in the drawing, it will be assumed that the subscriber at station A initiates a call. In so doing, the removal of the receiver from the switchhook sets reed 30 in vibration, thereby causing it to intermittently close a contact in circuit with the winding of electromagnet 7. This circuit may be traced from battery through the winding of electromagnet 7, contact of cut-off relay 14, line conductor 6, and the vibrating reed 30 to ground. Impulses of current are thereupon transmitted through the winding of electromagnet 7 at a rate depending upon the rate of vibration of this 80 reed. Reed 20, controlled by electromagnet 7, is set in vibration as a result of the passage of these current impulses governed by reed 30 at station A through the winding of electromagnet 7, thereby causing the operation of relay 40, over a circuit from battery through the winding of relay 40, normal contact thereof, and reed 20 to ground. Relay 40, in operating, closes a locking circuit for itself from battery through the winding 90 of left-hand normal contact of relay 40, and the contact of jack 10 to ground. Relay 40, in operating, also causes the line lamp 30 to be lighted. The operator, in responding to the lighted condition of this line lamp, inserts a plug 15 into jack 10, thereby opening the lamp circuit of relay 40 and effacing the line lamp, and also causing the operation of cut-off relay 14, thereby disconnecting the electromagnet 7 from the line circuit.

In a similar manner, reed 21 responds to the vibration of the reed 31 when station B initiates a call and as a result the line lamp 51 is lighted. In a similar manner, line lamp 52 or 53 may be lighted.

From the above description it will be evident that this invention provides a very simple system in which the operator is enabled to determine which of a plurality of stations connected with the line circuit has

initiated a call. In thus being able to determine which of a plurality of stations has initiated a call the operator may, without any further action, make the proper notation for charging the call to the proper station. In systems heretofore used it has been necessary, when a station on a party line has initiated a call, for the operator to inquire of the calling subscriber the number of his station. It will be seen, therefore, that the system embodying the present invention is a decided improvement over systems heretofore employed.

What is claimed is:

- 15 1. A telephone system comprising a telephone line terminating at a central office, a plurality of subscribers' stations connected with the telephone line, means at each station for generating currents of different frequencies, an electromagnetic device selectively responsive to the currents so generated, and a signaling device at the central office individual to each station and selectively controlled by said device.
- 20 2. A telephone system comprising a telephone line terminating at a central office, a plurality of subscribers' stations connected with the telephone line, means comprising a tuned reed at each station for generating currents of different frequencies, an electromagnetic device at the central office selectively responsive to the currents so generated, and a signaling device at the central office individual to each station and selectively controlled by said device.
- 25 3. A telephone system comprising a telephone line terminating at a central office, a plurality of subscribers' stations connected with the telephone line, means including a tuned reed at each station for generating currents of different frequencies, an electromagnetic device including a plurality of tuned reeds selectively responsive to the currents generated at the stations, and a signaling device at the central office individual to each station and selectively controlled by said device.
- 30 4. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, a relay controlling each signaling device and selectively energized under control of said electromagnetic device, and a locking circuit for each relay completed upon energization thereof.
- 35 5. A telephone system comprising a telephone line terminating at a central office in a plurality of terminals, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device associated with each terminal and individual to each station, a relay controlling each signaling device and selectively energized under control of said electromagnetic device, a locking circuit for each relay completed upon energization thereof, a link circuit at the central office, and means actuated upon connection of the link circuit with the line terminal corresponding to an actuated line signaling device for opening the locking circuit of the actuated relay.
- 40 6. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, a relay controlling each signaling device and selectively energized under control of said electromagnetic device, and a locking circuit for each relay completed upon energization thereof.
- 45 7. A telephone system comprising a telephone line terminating at a central office in a plurality of terminals, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device associated with each terminal and individual to each station, a relay controlling each signaling device and selectively energized under control of said electromagnetic device, a locking circuit for each relay completed upon energization thereof, a link circuit at the central office, and means actuated upon connection of the link circuit with the line terminal corresponding to an actuated line signaling device for opening the locking circuit of the actuated relay.
- 50 8. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, a relay controlling each signaling device and selectively energized under control of said electromagnetic device, and a locking circuit for each relay completed upon energization thereof.
- 55 9. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, a relay controlling each signaling device and selectively energized under control of said electromagnetic device, and a locking circuit for each relay completed upon energization thereof.

office individual to each station and selectively controlled by said device.

60

5. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, and a relay controlling each signaling device and selectively controlled by said electromagnetic device.

70

6. A telephone system comprising a telephone line terminating at a central office, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device at the central office individual to each station, a relay controlling each signaling device and selectively energized under control of said electromagnetic device, and a locking circuit for each relay completed upon energization thereof.

75

7. A telephone system comprising a telephone line terminating at a central office in a plurality of terminals, a plurality of subscribers' stations connected with the telephone line, means at each station including a tuned reed set in motion upon the removal of the receiver from the switchhook for generating currents of different frequencies, an electromagnetic device including a plurality of tuned reeds selectively responsive to the currents so generated, a signaling device associated with each terminal and individual to each station, a relay controlling each signaling device and selectively energized under control of said electromagnetic device, a locking circuit for each relay completed upon energization thereof, a link circuit at the central office, and means actuated upon connection of the link circuit with the line terminal corresponding to an actuated line signaling device for opening the locking circuit of the actuated relay.

95

In witness whereof, I hereunto subscribe my name this 10th day of April A. D., 1917.

HENRY P. CLAUSEN.
